ELECTRIC CONNECTOR

Harold H. Boyer, Canton, Ohio, assignor to The
Hoover Company, North Canton, Ohio, a corpora-
tion of Ohio

Application August 21, 1937, Serial No. 160,236

1 Claim. (Cl. 173—322)

This invention relates to electric connectors, and an object of the invention is to provide a new and improved device of this character.

Another object of the invention is to provide an electric plug cap adapted to be employed in the bail portion of a suction cleaner handle.

A further object is to provide an electric plug having means for detachably anchoring one end of a cord strain relief member disposed about an electric cord connected to the plug cap.

Still further objects of the invention will be apparent from the following specification and accompanying drawing, wherein like numerals are employed to designate like parts throughout the several views.

Fig. 1 is a longitudinal vertical section through the bail of a suction cleaner handle;

Fig. 2 is a sectional view taken along the line 2—2 of Fig. 1;

Fig. 3 is a longitudinal vertical section through the handle of a suction cleaner, showing another embodiment of the invention; and

Fig. 4 is an end elevation with parts broken away of the electric connector shown in Fig. 3.

One embodiment of the invention is disclosed in Figs. 1 and 2 and is employed in a suction cleaner, not completely shown, having a hollow handle 13 detachably mounted in a split clamping socket 14 rigidly attached to a bail 15 provided with bifurcated arms 16 which are adapted to be pivoted to the body of the suction cleaner. The split socket 14 has a pair of ears 18 which receive a clamping screw 20 to rigidly secure the handle in the socket 14. The lower end of the handle is provided with an insulated positioning lug 21 which is received in the slot 19, formed between the ears 18, to properly position the handle in the socket 14. A cover 30 of insulating material is interposed between the socket 14 and the handle 13 to insulate the latter.

Removably disposed in the socket 14 is a male plug 60 comprising a body portion 61 molded in one piece out of electric insulating material, such as "Bakelite," and is provided with a longitudinally extending bore 62 terminating at its opposite ends in recesses 63 and 64, the recess 63 providing an annular flange 65 and a shoulder 66 on which is mounted male contacts 68 connected to motor leads 25 disposed in the opening 62. The motor leads 25 extend through aligned slots in the bail and socket and thence along one of the bail arms 16 to the suction cleaner motor, not shown. A positioning lug 42 is formed integrally with the plug body 61 and is received in the slot 19 to properly position the male con-

tacts 36 in the socket 14 with respect to the female contacts, not shown, disposed in the lower end of the handle 13 and connected to electrical conductors 28 extending upwardly through the handle to a source of current supply.

The motor leads 25 are reinforced and protected by a cord protector 45 formed of spring wire wound into a helix having a reduced diameter at 46 to receive loosely the motor leads 25, and has its fixed end of increased diameter to constitute in effect a flange 47 for anchoring the cord protector in the body of the electric plug 60.

To readily detachably secure the cord protector 45 to the electric plug body 61, a retaining member 70 is removably secured to the shoulder 69, formed by the recess 64, by means of a screw 71. The retaining member 70 is of electric insulating material and is provided with a bayonet or key-hole type of opening having a large section 72 merging into a smaller section 73.

In order to assemble the electric plug 60 and the cord protector 45 the latter is passed through the large opening 72 and is then bodily moved laterally into the smaller opening 73 which snugly embraces the reduced portion 46, while the enlarged end 47 is disposed in an arcuate slot 75 provided in the plug body 61. The enlarged end 47 of the cord protector abuts the retaining member 70 to prevent longitudinal displacement of the cord protector 45 through the reduced opening 73, and the inwardly extending portion 93 of the handle socket 14 abuts the reduced portion 46 of the cord protector to prevent lateral displacement of the latter from the smaller opening 73 into the larger opening 72 of the retaining member 70, to thereby anchor the cord protector in the electric plug 60.

The handle 13 is then inserted in the socket 14 with the positioning lug 21 in the slot 19 to insure proper registration of the male contacts 68 with the female contacts. The handle 13 is moved into socket 14 until the lug 21 clears the opening in the ears 18 to permit the insertion of the clamping screw 20 which will rest against the lug 21 preventing longitudinal movement of the male plug, female receptacle and handle in the socket 14.

Another embodiment of the invention is shown in Figs. 3 and 4 and comprises an electric plug 60 having a body portion 61 molded in one piece out of electric insulating material, such as "Bakelite," and is provided with recesses 63 and 64. Disposed in the recess 63 are the male contacts 68 mounted on the shoulder 66. Extending longitudinally through the plug body is an opening

82 communicating with a transverse slot 83 provided with an arcuate shoulder 84 to provide a seat for a portion of the enlarged end 47 of the cord protector 45.

In order to secure the cord protector 45 to the plug body 81, a retaining member 88 is disposed in the recess 84 and is detachably secured to the plug body 81 by means of a screw 87 and is provided with an elongated slot 88 to receive and support a portion of the enlarged end 47 of the cord protector 45.

To assemble the plug 80 and the cord protector 45, the retaining member 88 is removed and the cord protector is inserted in the arcuate slot 83 until the enlarged end 47 rests on the arcuate shoulder 84, the retaining plate 88 is then secured to the plug cap so that the enlarged end 47 of the cord protector 45 is supported by the defining edge 91 of the recess 88. The plug body 81, handle 13 and female contacts are then properly disposed in the socket 14.

It will be understood that various changes in the size shape and arrangement of parts may be resorted to without departing from the spirit of the invention or scope of the appended claim.

I claim:

In a device of the character described, a socket, an electric connector in said socket and having a body provided with a bore for an electric cord, 5 a cord protector about said cord and having an enlarged and reduced portion, a shoulder formed on said cord protector by said enlarged and reduced portions, a retaining member detachably mounted on said body and having an opening spaced from its marginal periphery and communicating with said bore, said opening being so constructed with respect to said enlarged portion of said cord protector for passing said enlarged portion longitudinally therethrough and thence 10 laterally of said opening, whereby the defining wall of said opening engages said shoulder to hold said cord protector against longitudinal movement through said opening, and means carried by said socket for abutting said reduced portion to prevent lateral movement of said cord protector in said opening.

HAROLD H. BOYER.
